(57) **CLAIM**

The ornamental design for an air conditioning refrigerant charging device with digital gauge, as shown and described.

DESCRIPTION

FIG. 1 is a front perspective view of an air conditioning refrigerant charging device with digital gauge in accordance with the claimed design;

FIG. 2 is a left side elevation view thereof;

FIG. 3 is a right side elevation view thereof;

FIG. 4 is a top view thereof;

FIG. 5 is a bottom view thereof;

FIG. 6 is a rear elevation thereof; and,

FIG. 7 is a front elevation view thereof.

The broken lines in the FIGURES represent unclaimed subject matter and form no part of the claimed design.
